(57) **CLAIM**

The ornamental design for an electronic atomizing device assembly with power supply and atomizer, as shown and described.

DESCRIPTION

FIG. 1 is a perspective view of the electronic atomizing device assembly with power supply and atomizer shown in an assembled configuration according to the first embodiment of my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is an enlarged top plan view thereof;

FIG. 8 is an enlarged bottom plan view thereof;

FIG. 9 is a perspective view of the electronic atomizing device assembly with power supply and atomizer as shown in FIG. 1, with atomizer removed from the assembly for clarity of disclosure;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is an enlarged top plan view thereof;

FIG. 16 is an enlarged bottom plan view thereof;

FIG. 17 is a perspective view of the electronic atomizing device assembly with power supply and atomizer as shown in FIG. 1, with power supply removed from the assembly for clarity of disclosure;

FIG. 18 is another perspective view thereof;

FIG. 19 is a front elevational view thereof;

FIG. 20 is a rear elevational view thereof;

FIG. 21 is a left side elevational view thereof;

FIG. 22 is a right side elevational view thereof;

FIG. 23 is an enlarged top plan view thereof;

FIG. 24 is an enlarged bottom plan view thereof;

FIG. 25 is a perspective view of the electronic atomizing device assembly with power supply and atomizer shown in an assembled configuration according to the second embodiment of my new design;

FIG. 26 is another perspective view thereof;

FIG. 27 is a front elevational view thereof;

FIG. 28 is a rear elevational view thereof;

FIG. 29 is a left side elevational view thereof;

(Continued)

FIG. 30 is a right side elevational view thereof;
FIG. 31 is an enlarged top plan view thereof;
FIG. 32 is an enlarged bottom plan view thereof;
FIG. 33 is a perspective view of the electronic atomizing device assembly with power supply and atomizer as shown in FIG. 25, with atomizer removed from the assembly for clarity of disclosure;
FIG. 34 is another perspective view thereof;
FIG. 35 is a front elevational view thereof;
FIG. 36 is a rear elevational view thereof;
FIG. 37 is a left side elevational view thereof;
FIG. 38 is a right side elevational view thereof;
FIG. 39 is an enlarged top plan view thereof; and,
FIG. 40 is an enlarged bottom plan view thereof.
The broken lines in the drawings depict portions of the electronic atomizing device assembly with power supply and atomizer that form no part of the claimed design.
The oblique shade lines in the figures show transparency.
